UNITED STATES PATENT OFFICE.

WALTER S. LAKE, OF KANSAS CITY, MISSOURI.

BELT FASTENER.

Application filed December 1, 1924. Serial No. 753,182.

To all whom it may concern:

Be it known that I, WALTER S. LAKE, a citizen of the United States, and a resident of Kansas City, county of Jackson, State of Missouri, have invented a certain new and useful Improvement in Belt Fasteners, of which the following is a complete specification.

This invention relates to belt-fasteners and my object is to produce a belt-fastener which may be readily and easily inserted and secured in position, and which in use will provide a completely flexible hinge connection that will pass over belt pulleys without subjecting them to unusual wear or knock.

Another object is to produce a fastener of such construction that the pull on opposite ends of a belt will be exactly counterbalanced, this construction leading to a lengthening in the life of the belt.

A further object is to produce a fastener which may be conveniently sold in rigid form, but which upon application to a belt will immediately recover its flexible nature and provide a hinge connection for adjacent ends of a belt.

A still further object is to provide a strong, durable, efficient and inexpensive belt-fastener, primarily intended for use with the belt-fastening machine illustrated and described in my copending applications for Patents, Ser. No. 603,620, filed November 27, 1922, and Ser. No. 659,522, filed August 27, 1923; and in order that the invention may be fully understood, reference is to be had to the accompanying drawing, in which:—

Figure 1 is a top plan view of a fastener embodying the invention as it will appear after being secured on a belt.

Figure 2 is an edge view of the same.

Figure 3 is a top plan view of the fastener.

Figure 4 is a section on the line IV—IV of Figure 3.

Figure 5 is a plan view of the hinge pin.

Figure 6 is a plan view of one of the fastening laces.

Figure 7 is a side elevation of one of the laces.

In the said drawing, where like reference characters identify corresponding parts in all of the figures, 1 indicates a pivot pin which is formed throughout its length with a series of equi-spaced reduced circumferential portions 2.

The lace members of the invention comprise a plurality of similar wire laces bent to form pivot loops 3, said loops being twisted so that their straight portions 4 shall lie parallel and in the same plane. The ends of the wire laces are parallel, down-turned, and inclined toward the loop to form belt-engaging hooks 5 (see Figures 4 and 7). Pairs of said lace members are interlocked by engaging their looped portions 3, slid onto the pivot pin 1 and fitted in one of the reduced portions 2, which are of such width as to snugly receive the looped and interlocked wire laces, and then said looped portions are crimped to reliably secure them in position against dislodgment either longitudinally of the pin or longitudinally of each other (see Figure 3).

As soon as all of the reduced portions 2 of the pin 1 have been equipped with lacing wires, the fastener is preferably secured rigidly in the position shown in Figure 3, by treating it with a light coat of any suitable adhesive or cement (not shown). In this connection it is to be noted that the pivot pin 1 is formed with projecting ends 6 for reception in the belt-fastening machine of my copending application above-identified.

The device as a unit (held by the cement) is inserted in the belt B by the use of the machine, the inclined hooks 5 being readily pressed through the belt from the top side thereof, and upon contact with the base of the machine are crimped as shown in dotted lines in Figure 2. It will be apparent when the belt is inserted in operative position, that immediately it passes over a pulley, the adhesive or cement securing the fastener in fixed relation, will be ruptured, the parts then being freed for operation as a hinge.

With the fastener of the invention, referring particularly to Figure 1, it will be noted that the pull exerted by each wire lace is exactly counterbalanced by the pull of its companion lace, and this is due to the fact that the force exerted by each lace is diametrically opposite that of its companion lace. This result is accomplished due to the interlocking of the laces, as distinguished from a construction in which the pull on adjacent ends of the belt is off center with respect to each other. It will be readily apparent that if the force is equally applied along the whole width of the belt at its adjacent ends, the wear on said belt due to friction

tion will be equally distributed over the entire wearing surface, as distinguished from an uneven pull at one point leading to a rapid wear and deterioration at that point.

5. From the above description it will be apparent that I have produced a device of the character described which possesses all of the features of advantage set forth as desirable, and while I have described and 10 claimed the preferred embodiment of the same, I reserve the right to make all changes properly falling within the spirit and scope of the appended claims.

I claim:

15. 1. A belt fastener comprising a pivot pin, and a plurality of metallic laces arranged in pairs and pivotally secured to and extending in opposite directions from said pin, the opposed laces of each pair being arranged to 20 apply their pulling strain at diametrically opposite sides of said pin.

2. A belt fastener comprising a pivot pin, a pair of metal laces looped midway their 25 lengths and interlocked and applying pressure on the pivot pin at diametrically opposite sides and extending in opposite directions, each lace comprising a pair of straight portions having belt-engaging hooks and lying in the same horizontal plane, the straight 30 portions of the opposed laces being in longitudinal alinement.

3. A wire belt lace looped midway its 35 length and twisted and terminating in a pair of belt-engaging points and a pair of straight portions, the points respectively and the straight portions respectively being par-

allel and in the same plane and extending in the same direction.

4. A belt fastener comprising a pivot pin, and a plurality of metallic looped laces, said 40 laces being interlocked and arranged in pairs on opposite sides of and pivotally engaging the pin, the looped portion of each lace being adapted to apply its pull on the pin at a point diametrically opposite that of its 45 companion lace, and each lace terminating in a pair of hooks adapted to engage the belt at points in alinement with the hooks of its companion lace.

5. A belt fastener comprising a pivot pin 50 formed with a plurality of reduced circumferential portions, and a plurality of metallic laces, said laces being interlocked and arranged in pairs on opposite sides of and pivotally engaging the pin within a reduced 55 portion, the looped portion of each lace being adapted to apply its pull on the pin at a point diametrically opposite that of its companion lace, and each lace terminating in a pair of hooks adapted to engage the belt at 60 points in alinement with the hooks of its companion lace.

6. A belt fastener comprising a pivot pin, and a plurality of metallic laces arranged in pairs and pivotally secured and cemented to 65 and extending in opposite directions from said pin, the opposed laces of each pair being arranged to apply their pulling strain at diametrically opposite sides of said pin.

In witness whereof I hereunto affix my 70 signature.

WALTER S. LAKE.
